UNITED STATES PATENT OFFICE.

JASON C. STEARNS, OF WORCESTER, MASSACHUSETTS.

ELECTRICAL CONNECTOR OR SOCKET.

1,137,295.

Specification of Letters Patent. Patented Apr. 27, 1915.

Application filed March 23, 1912. Serial No. 685,708.

To all whom it may concern:

Be it known that I, JASON C. STEARNS, a citizen of the United States, residing at Worcester, in the county of Worcester and

5 State of Massachusetts, have invented a new and useful Electrical Connector or Socket, of which the following is a specification.

This invention relates to an electrical connector or socket for general use, but particularly adapted for use in making the electrical connections on automobiles, or for mounting incandescent lamps.

The principal objects of the invention are to provide an exceedingly simple and inexpensive form of connector which has some features that can be used also on switches and sockets. Also to provide a construction of a simple cylindrical form externally so that it can be inserted in a bored hole in 20 the wall to which it is to be applied.

Further objects and advantages of the invention will appear hereinafter.

Reference is to be had to the accompanying drawings, in which—

25 Figure 1 is a side elevation of a preferred embodiment of the invention. Fig. 2 is a similar view showing the parts in central longitudinal cross section. Fig. 3 is a side elevation showing the several elements removed from each other, and Fig. 4 is a side view partly in section showing a modification.

The invention is shown as comprising an external cylindrical casing 10 of sheet metal 35 having a transverse flat flange 11 by which it can be secured to a plane surface. This flange is preferably integral with the cylindrical portion of this casing. This casing is provided with slots 12 constituting a bayonet joint for receiving a plug 14 having projecting pins 15 oppositely located to enter said slots and complete the bayonet joint. The plug is shown as consisting of a block 40 of insulating material having two terminals, anchoring elements, or current carriers 16 of cylindrical form and made of metal which tightly fit in perforations extending through the plug 14, their ends being flush with one end of the plug. These terminals 45 have sockets 17 in the opposite end having screws 18 for securing the ends of a pair of conductors therein. This insulating block is shown as provided with an armor 19 comprising a brass cylinder having slots 20 for the pins and adapted to slide on the block to expose the screw heads. This metallic cyl-

inder is provided with a screw-thread 21 at the end for receiving a metallic member 22 which has an ogee shape in cross section with the end spaced from the end of the 60 plug 14 so as to be adapted to hold the cable conductor or the like passing into its end and bind it down to the end of the insulating block and prevent displacement of the terminals and cross circuiting without any 65 danger of bending the conductors sharply at any point. This member is normally spaced from the plate 11 to permit the whole thing to move in and out in order to disengage it from the bayonet joint.

70 Mounted in the other end of the cylindrical casing 10 is an insulating plug 25 which may be an ordinary electrical connecting plug, or an Edi-swan incandescent lamp base, or the like. This plug has a pair of socket 75 terminals 26 projecting from the end thereof and adapted to receive wires or cables therein which can be fastened by screws 27. Inside the casing this plug is provided with a pair of plungers 28 pressed inwardly by 80 springs 29 and connected with the two terminals. These plungers are adapted to engage the flat surface of the first mentioned plug so as to apply spring pressure thereto when the latter is inserted and to keep the two plungers resiliently pressed against the 85 conducting terminals thereof when it is moved around into the bayonet joint.

It will be seen that this device can be 90 placed in a bored hole in the wall and fastened to the outside thereof in a very simple manner; that the terminals are kept in firm contact with each other by spring pressure; and that the same springs act to hold the removable plug in its locked position in the 95 bayonet joint.

Another form of the external connection is shown in Fig. 4. In this case the plug 30 which fits within the casing is entirely composed of insulating material, as hard rubber, and is provided with a collar 31 beyond the end of which is a screw-thread made on the surface of the hard rubber. A cable or other conductor is led into the terminals through an insulating bushing 34 which screws on 100 the screw-threads up against the collar. Otherwise the construction and operation are the same.

105 Although I have illustrated and described only two forms of the invention, I am aware that many modifications may be made therein by any person skilled in the art without 110

departing from the scope of the invention as expressed in the claims. Therefore, I do not wish to be limited to all the details of construction herein shown and described, but

5 What I do claim is:—

1. As an article of manufacture, an electrical connector comprising a cylindrical casing, a removable plug in the end of the casing provided with terminals, said removable plug being provided with sockets at its end for receiving a pair of conductors and having an external circumferential enlargement at the end beyond the end of the casing, a cylindrical armor fitting freely between said plug and casing, and fitting against the edge of said enlargement, and having an external screw thread at the end, and a member adapted to be received by said screw thread and having a central opening 29 in the end through which the conductors may enter, said member being provided with a surface curved inwardly toward the central opening and spaced from the screw-threaded end for engaging the conductors and holding them firmly in position.
2. As an article of manufacture, an electrical connector comprising a cylindrical casing, a cylindrical plug entering the end of

the casing and adapted to be held therein and having terminals in one end, and sockets 50 in its other end for receiving conductors, said sockets being provided with screws for holding the conductors in position, and an armor cylinder slidably mounted on said plug, located inside said casing but projecting from the end thereof, to permit the screw heads to be exposed by the sliding of the armor from over them.

3. As an article of manufacture, an electrical connector or socket comprising a casing, a plug adapted to be inserted in the end of the casing and having a radial pin projecting from its surface, said casing having means for engaging said pin and holding the plug in position, said plug being of insulating material, and a metallic armor longitudinally slidable thereon and provided with a longitudinal slot for said pin.

In testimony whereof I have hereunto set my hand, in the presence of two subscribing 50 witnesses.

JASON C. STEARNS.
